[57] CLAIM

The ornamental design for a display for a plurality of objects, as shown and described.

DESCRIPTION

FIG. 1 is a perspective view of my new design for a display for a plurality of objects;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof;

FIG. 8 is an enlarged partial sectional view of FIG. 1 taken along line 8—8;

FIG. 9 is an enlarged partial view of FIG. 8 taken along line 9—9 of FIG. 8;

FIG. 10 is a top view of FIG. 9;

FIG. 11 is a perspective view of a second embodiment of my new design for a display for a plurality of objects;

FIG. 12 is a front view thereof;

FIG. 13 is a left side view thereof;

FIG. 14 is a right side view thereof;

FIG. 15 is a top view thereof;

FIG. 16 is a bottom view thereof; and,

FIG. 17 is a rear view thereof;

FIG. 18 is a partial sectional view along line 18—18 in FIG. 11;

FIG. 19 is a partial view along line 19—19 in FIG. 18; and,

FIG. 20 is a top view of FIG. 19.
